ATTACHING SOLES TO WELTED SHOES

George T. Hart, Jr., Lynn, Mass., assignor to
United Shoe Machinery Corporation, Flemington, N. J., a corporation of New Jersey

Application May 23, 1944, Serial No. 536,857

3 Claims. (Cl. 12—142)

1

This invention relates to methods of attaching outsoles to welted shoes, and more particularly to methods of attachment by means of cement activated in situ by a high-frequency electrostatic field. The invention also relates to an electrode structure particularly useful for this purpose.

It is well known that soles may be attached to shoes by means of a cement which is activated in situ by the application thereto of a high-frequency electrostatic field which produces heat directly in the cement. Such methods have commonly been applied to shoes of the McKay type in which the edge of the sole is close to the periphery of the shoe last with the inherent result that the sole and shoe are firmly held together during the activation of the cement by pressure applied to the outsole and to the last within the shoe. These methods are not applicable to welted shoes, however, in which the outstanding welt strip is unsupported by the last and in which, consequently, there is no assurance that this strip will be held in engagement with the outsole during the activation of the cement. While those methods employing a stray field to activate the band of cement in the forepart of the shoe provide many advantages, they are subject to the production of unused amounts of heat generated in the non-cemented mid-portions including the filler.

When attaching outsoles to such shoes by means of a solvent-activated cement, it is the custom to apply pressure to the outstanding welt by means of a welt-holddown member closely surrounding at least the forepart of the shoe, and pressure is applied through this holddown member to keep the welt strip in firm contact with the outsole.

One important object of the invention is to devise an improved method of attaching outsoles to welted shoes which makes it possible to activate the cement in situ while pressure is applied to keep the welt in firm contact with the sole.

In one aspect my invention contemplates a novel method in which pressure is applied to clamp together the welt strip, a holddown electrode extending around at least the forepart of the shoe and with the help of which an electrostatic field is set up traversing the band of attaching cement and the outsole, and then activating the cement.

In another aspect, invention will be found in utilizing the welt holddown both for the production of a direct field in the forepart only and for the transfer of clamping pressure to the welt in that area while the activation of cement in the

2

shank portion is advantageously effected by means of a stray field which is little affected by the metal of the shank piece. Such a method is applicable to those welted shoes in which the welt extension on the shank portion of the shoe is not sufficiently great to require the application of clamping pressure to the welt strip.

These and other aspects of the invention will now be discussed in the following specification taken in connection with the accompanying drawings, in which

Fig. 1 is an angular view, illustrating the application of cement to an outsole;

Fig. 2 is a similar view, illustrating the application of cement to a shoe bottom;

Fig. 3 is a transverse vertical section through the forepart of a shoe positioned in a sole attaching machine modified for the utilization of applicant's method;

Figs. 4, 5 and 6 are transverse sections of the forepart of a shoe, in the bottom structure of which an electrode strip has been embodied for cooperation with a welt-holddown electrode; and

Fig. 7 is a diagrammatic plan view of an electrode pad facilitating the application of a direct field to the band of cement around the forepart of the shoe and of a stray field to the shank portion of the shoe.

In preparing the bottom of a lasted shoe S having an outstanding welt strip 12 for the attachment thereto of an outsole 14, it is common practice to apply to the attaching face of the welt strip a band of cement 16 (Fig. 2) which ordinarily will extend over the edges of the inseam 18. This may be applied by means of a hand brush 20 or in any other desired fashion. When the sole is to be attached by means of a thermoplastic cement which may be activated in a high-frequency electrostatic field, the cement utilized will be of a type which may be activated in situ after the sole has been pressed against the shoe and can be one of the vinylite resin types of cement, although there are many others which are applicable. The preparation of the shoe bottom also includes the application of shoe filler material 22 to the forepart of the shoe and frequently includes the application of a shank piece 24 which may be of fiber, wood or even metal. In some cases, it will be found desirable and convenient to include an electrode strip 26 such as of metal foil in the shoe bottom closely adjacent to the inner periphery of the inseam, and to provide a lead 27 by which it can be connected to one side of an oscillator. This strip may be held in a suitable manner as by an adhesive which

needs only to be strong enough to hold the strip in place until the sole is attached. A band of cement 30 will also usually be applied to the peripheral margin of the outsole 14 by means of a hand brush 32 or in any other desired way.

After these coatings of cement have dried, they then being hard and non-tacky, thereby facilitating the correct positioning of the outsole with respect to the shoe bottom, the shoe 5 and the outsole 14 will be brought together in a sole-attaching machine, such as the one illustrated in Letters Patent of the United States No. 2,138,960, granted December 6, 1938, upon the application of Sidney J. Finn. The pad cover 34 (Fig. 3) of such a machine may then embody an electrode plate 36 having the general shape of and underlying the forepart of a shoe to be applied to the machine. In some cases this plate will extend the full length of a sole. Such a plate will be of flexible metallic material and will usually be slightly smaller than the peripheral outline of the smallest sole to be applied in the machine. A wire lead 38 attached to the plate 36, in any convenient location, will extend outwardly of the pad for a purpose to be later described. Pressure may be applied to the shoe bottom by way of the last through various members including a toe pad 40 and to the welt through a hold-down member 42 extending around at least the forepart of the shoe and contacting substantially the whole width of the grain or upper surface of the welt strip 12. Frequently, such a welt hold-down will be slightly flexible and usually will be of electrically non-conductive material so that an outer electrode 44 which may be in the form of a wire or cable may be embodied directly in the welt hold-down itself. If the hold-down itself is conductive, then the cable will have an insulating cover. To such an electrode, a convenient lead 46 will be applied to enable its attachment to a source of supply of high-frequency current such as an oscillator (not shown). In using this arrangement, as pressure is applied from above or below to clamp the welt firmly in contact with the outsole, a high-frequency electrostatic field will be set up between this electrode 44 and the plate 36 which will pass substantially vertically of the shoe through the band or bands of cement previously applied. The production of heat in this cement will take place rapidly, enabling the cement to be activated in situ and will not require the time necessary for the dissipation of a solvent as is the case when solvent-activated cements are employed. Owing to the shape and location of the electrodes the part of the field which extends over into the mid-portions of the forepart of the shoe is much weaker than the part of the field which passes directly through the band of cement, with the inherent result that the amount of heat which is generated in the mid-portion is small. This constitutes an advantage of the application of the direct field in the forepart of the shoe, as compared to the use of the fringe field in the forepart which, as it has been used in previous cases, produces unused heat in said mid-portions, although the fringe field may have other advantages, making it desirable for certain purposes.

In some instances, it may be preferred to cause the electrostatic field to pass horizontally through the layer of attaching cement from edge to edge thereof, and this can readily be accomplished when an electrode strip 26 has been embodied in the shoe bottom, as shown in Figs. 2 and 4. In some instances, it may be found preferable to

apply a wire electrode 26' (Fig. 5) to the shoe bottom in place of the strip of foil, and such a wire electrode will usually be laid against the inner face of the inseam and held there, it may be, by the stickiness of the shoe filler material. The method of sole attaching involving the use of an electrode incorporated in the shoe bottom and extending along the inner edge of the cement band positioned between the welt and an applied sole is claimed in a divisional application, Serial No. 731,077, filed February 26, 1947, in my name. In the use of arrangements shown in Figs. 4 and 5, the field will be understood to extend from the hold-down electrode 44 to the shoe bottom electrode 26 or 26' substantially horizontally and substantially in the plane of the attaching cement. In other instances, it may be found desirable to cause the field to be more exactly in the plane of the attaching cement, and this may readily be accomplished by supporting a similar outer electrode 44' (Fig. 6) by means of brackets 48 extending outwardly and downwardly from the welt hold-down 42'. It will be understood that, with this arrangement, either an inner electrode strip of foil 26 may be employed or the wire 26' shown in Fig. 5.

The design of cement shoes frequently is such that the extension of the welt in the shank portion of the shoe is considerably less than it is in the forepart of the shoe, so that it is not necessary to use a welt hold-down in this portion of the shoe bottom. When that is the case, an electrode pad such as that shown at 50 in Fig. 7 will be substituted for the pad cover 34 of Fig. 3. Such a pad will be provided with a forepart plate 52 corresponding to the plate 36 and, combined with it, will have a stray-field-electrode structure 54 including interdigitated strips 56 and 58, alternating strips being interconnected and provided with outwardly extending leads 60 and 62. The strips 58 will also be connected to the forepart plate 52 by a lead 64 which may be buried in the pad. Inasmuch as the bars 56 and 58 of the stray-field electrode 54 extend transversely of a shoe bottom, the field produced by them will be little affected by any metal in the shank piece. It will be understood that, in the use of this pad, the forepart field will be set up between a hold-down electrode 44 and the plate 52, as in the arrangement shown in Fig. 3, thereby producing a direct field in this portion of the shoe while, in the shank portion, the stray field bulging upwardly from the pad will activate the cement bands along the sides of the shank portion of the shoe. In the use of such an electrode, the electrode member 44 will be connected to the same side of the oscillator (not shown) as is the electrode lead 60, while the lead 62 will be joined to the other side thereof. The effectiveness of the preceding method is further enhanced by the fact that the configurations of the two types of fields in the respective portions of the shoe to which they are applied are particularly adapted to the efficient conversion of electrical energy into heat energy confined substantially only to the cemented areas. The reason for the efficiency of the marginal direct field in the forepart has already been stated. As to the utilization of the stray field in the shank, since the width of the sole of the shank is such that the band of cement extends substantially over the entire area thereof, leaving only a narrow non-cemented strip in the mid-portion, the stray field directly encounters only a small non-cemented area into which it may pass, thus resulting in small loss of heat.

Having thus described my invention, what I claim as new and desire to secure by Letters Patent of the United States is:

1. That improvement in methods of attaching outsoles to shoes having welt strips attached thereto by inseams, which consists in bringing together an outsole and the welt strip of a shoe to at least one of which a band of cement has been applied directly beneath the welt strip, bringing an insulated hold-down electrode into contact with substantially the whole width of the upper face of the welt strip, forcing together said electrode, the welt strip and the outsole, and heating the cement in situ by passing a high-frequency electrostatic field directly through the band of cement and extending from said insulated hold-down electrode to another electrode outside the outsole.

2. That improvement in methods of attaching soles to welted shoes, which consists in bringing together an outsole and a shoe having an outstanding welt strip with a layer of cement interposed between the welt strip and the outsole, activating said cement by means of a direct field in the forepart of the shoe extending through the cement band around the forepart, and simultaneously activating the cement in the shank portion of the shoe by means of a stray-field electrode positioned entirely beneath the outsole.

3. That improvement in methods of attaching

10

outsoles to shoes having an outstanding welt strip, which consists in securing a shank piece to the bottom of the shank portion of the shoe, applying a bottom filler to the forepart of the

15 shoe bottom, applying a coat of cement to the attaching surface of the welt strip, applying a coat of cement to the marginal portion of an out-

sole, bringing together said outsole and shoe after

the cement has dried, applying a hold-down elec-

trode to the exposed surface of the outstanding

welt, pressing the sole into contact with the shoe

bottom, clamping together the electrode, the welt

and the outsole, setting up a direct high-fre-

quency electrostatic field to heat the cement in

the forepart of the shoe with the aid of said hold-

down electrode, and setting up a stray field to

heat the cement in the shank portion of the shoe.
